DESIGN FOR A DRINKING GLASS

Margarita M. Maguin, New York, N. Y.

Application June 3, 1942, Serial No. 107,092

Term of patent 3½ years

To all whom it may concern:

Be it known that I, Margarita M. Maguin, a citizen of Colombia, South America, residing at New York, N. Y., have invented a new, original, and ornamental Design for a Drinking Glass, of which the following is a specification, reference being had to the accompanying drawings, forming part thereof.

Fig. 1 is a face view of a drinking glass, showing my new design. Fig. 2 is a rear elevational view. The glass is circular in cross-section. The features shown are fanciful and do not represent any living individual.

I claim:

The ornamental design for a drinking glass, as shown and described.

MARGARITA M. MAGUIN.
